UNITED STATES PATENT OFFICE

2,417,401

CONTAINER DOOR STOPPING AND
SUPPORTING DEVICEHenry Steinhorst, Utica, N. Y., assignor to Emil
Steinhorst & Sons, Inc., Utica, N. Y., a corpora-
tion of New York

Application December 21, 1944, Serial No. 569,229

1 Claim. (Cl. 217—60)

1

My invention relates to a door stopping and suspending device, and I declare the following to be a full, clear, concise and exact description thereof sufficient to enable anyone skilled in the art to which it appertains to make and use the same, reference being had to the accompanying drawings in which like parts are referred to by like numbers throughout the specification.

The object of the invention is to provide a door stopping and suspending device for use more particularly in connection with the swinging doors of refrigerators and for freezers used in the home or on the farm. It will be found useful on any cabinet where a swinging door is used. The device is designed to limit the angle to which the door is opened and to hold it at said angle until it is desired to close the door.

Furthermore, the device is designed to take up very little room in the compartment where installed. It is so disposed as not to interfere with the storage of vegetables or other articles placed in the refrigerator or freezer.

The object will be understood by referring to the drawings, in which:

Figure 1 is a side elevation of the door stopping and suspending device as applied to a door of a refrigerator or freezer, parts being broken away.

Figure 2 is a detail view, showing a perspective of a spring employed in the device.

Figure 3 is a detail enlarged view showing a perspective of the hinge member employed.

Figure 4 is a detail enlarged view of a bolt employed in the construction.

Referring more particularly to the drawings, the stopping and suspending device embodies a spring 1 made preferably of spring steel. The spring 1 is mounted by bolts hereinafter mentioned and has formed on its lower end a rectangular shaped recess 2. Aperture 2 allows for the projection of the entire width of tongue 3 of split hinge holding member 4 fastened by screw bolts 6 to the frame member 7 of the refrigerator or freezer 8, whereby said spring 1 can rock on tongue 3 as a pivot.

The upper end 9 of spring 1 is equipped with an open annular aperture 10 made therein. A long narrow open slot 12 made in spring 1 and extending a little over half its length opens into the larger annular aperture 10. A bolt 16 having an annular head 17 is held to the inner lining plate 18 in the body part 20 of door 21 of the freezer 8. It is located near the center part of plate 18.

Door 21 is hinged at 25, 25 to the casing 26

2

of the freezer 8. Furthermore, said bolt 16 has formed integral therewith and adjacent to the head 17 thereof, two annular shoulder rings 27 and 28, which are smaller in diameter than head 17 and progressively diminish in diameter, ring 28 being the smaller. The larger ring 27 nearest head 17 will occupy the space within aperture 10 in the upper end of spring 1 when door 21 is in open position or suspended at an angle to frame 7, as shown in Fig. 1. The smaller ring 28 will occupy the space of narrow slot 12 as it slides along the spring 1, when moving the door 21 to closed position.

A bolt 30 having a half oval head is held by a nut 31 to the inner lining plate 18. It is located back of spring 1 and adjacent to the lower edge of door 21, whereby to exert a pressure outwardly on spring 1 when door 21 is in open position. This outward pressure will cause the upper end 9 of spring 1 to spring forward automatically, whereby ring 27 of bolt 16 will occupy the space of aperture 10 of said end 9, when the door 21 is in open position, as shown in Fig. 1.

In operation, assuming the door stopping and suspending device has been installed as shown in Fig. 1 to a refrigerator or freezer 8, the operator will open door 21 in the usual way. As said door 21 swings upward on its hinges 25, 25 into the limiting position as shown in Fig. 1, the end 9 of spring 1 under stress exerted by the head of bolt 30 will spring automatically forward and engage ring 27 of bolt 16 at aperture 10 and, thereby hold said door 21 at the predetermined angle as shown in Fig. 1.

In order to close door 21 it will be necessary only to press manually on the upper end 9 of spring 1 and push it towards the plate 18 of door 21, whereby to free end 9 from ring 27 and then push the door 21 to closed position. As door 21 rocks downward, ring 28 of bolt 16 will slide along open slot 12 in spring 1.

Having thus described my invention, what I claim as new and useful and desire to secure by Letters Patent is:

45 The combination of a freezer, a hinged door therefor and a door stopping and supporting device in open position comprising a hinge member on said freezer, a flat strap-like spring member having an aperture in one end thereof for the pro-
jection therethrough of said hinge member, said spring member having formed therein a long nar-
row slot terminating in an annular aperture, a bolt having shoulder rings of different diameter formed thereon mounted on said door, one of said shoulders adapted to slide in said long narrow slot

in said spring, when said door is moved from closed position to open position the other shoulder ring adapted to engage said spring at said annular aperture, and a bolt mounted on said door, and the head of said last named bolt lying between said door and said spring, engaging said spring, whereby to force said spring outwardly to lock said other shoulder ring in said annular aperture and to allow the spring to hold the door in open position.

HENRY STEINHORST.
